[57] **CLAIM**

The ornamental design for a stitching pattern for a palm surface of work glove, as shown and described.

DESCRIPTION

FIG. 1 is a perspective view showing my ornamental design for a palm surface of a work glove;

FIG. 2 is a front view thereof;

FIG. 3 is a left side view thereof;

FIG. 4 is a right side view thereof; and,

FIG. 5 is a top front perspective view thereof.

The broken line showing of the work glove is for illustrative purposes only and forms no part of the claimed design.
